CLAIM

We claim the ornamental design for a device for attaching and detaching needle to/from syringe, as shown and described.

DESCRIPTION

FIG. 1 is a front and top perspective view of a device for attaching and detaching needle to/from syringe of the present invention;

FIG. 2 is a rear and bottom perspective view thereof;

FIG. 3 is a front view thereof;

FIG. 4 is a rear view thereof;

FIG. 5 is a first side view thereof;

FIG. 6 is a second side view thereof;

FIG. 7 is a top view thereof; and,

FIG. 8 is a bottom view thereof.

The broken lines shown represent unclaimed subject matter and form no part of the claimed design. Additionally, the unevenly broken lines in the drawings define the limits of the claimed design.
